UNITED STATES PATENT OFFICE.

CHARLES A. MORRIS, OF BLOOMFIELD, NEW JERSEY.

SUBMARINE EXCAVATOR.

SPECIFICATION forming part of Letters Patent No. 391,331, dated October 16, 1888.

Application filed April 19, 1886. Renewed July 11, 1888. Serial No. 279,672. (No model.)

To all whom it may concern:

Be it known that I, CHARLES A. MORRIS, of Bloomfield, in the county of Essex and State of New Jersey, have invented an Improvement in Submarine Excavators, of which the following is a specification.

This invention relates to that class of submarine excavators in which the bucket or grapple is opened by the weight of the parts as they hang suspended by one chain, and in which the bucket or grapple is closed by drawing upon the other chain, the said chain acting by leverage to close the bucket and to keep it closed while the same is being hoisted.

The improvements are available with a bucket having four sections that close toward each other and form a hemispherical bucket, and also to an excavating apparatus in which grapple-teeth take the place of the bucket-sections. I make use of a central joint-block to which the four sections are hinged, and a head-block and peculiar toggle-arms reaching from the head-block to the grapple-sections, and the joint-block receives a frame that supports the chain wheels and drums that act to close the buckets, the chain to the chain-wheels passing through the head-block, and to this head-block the opening-chain is connected.

In the drawings, Figure 1 is an elevation of the apparatus. Fig. 2 is a plan view of the apparatus, the head-block, and toggle-arms, and stop-bars being removed. Fig. 3 is a separate plan view of the head-block. Fig. 4 is a section of the same at the line *x x*. Fig. 5 is a section of the joint-block and wheel-frame with one wheel and drum in elevation. Fig. 6 is a separate plan view of the joint-block; and Fig. 7 shows, in smaller size, a plan of the wheel-flange and the stop-bars extending out from the same.

The joint-block A is made with the jaws 2 2, 3 3, 4 4, and 5 5, for the knuckles 6 upon the claw-shaped arms B, that extend outwardly and then downwardly. The lower ends of the arms usually taper toward the vertical central line of the machine, so as to approach each other, and these claw-shaped arms are provided with flanges 7, upon which are riveted or bolted the grapple sections D E F G. These sections, when closed toward each other, form a bucket of nearly hemispherical shape, and there being four sections each section is nearly

a quarter of such hemisphere, the lines of separation corresponding generally to vertical planes intersecting each other at right angles and passing through the vertical center of the machine, the edges lapping slightly. The joint-block is made of two main parts, either cast or forged and having downwardly-projecting flanges 10, by which they are bolted or riveted together, and within the upper flanges, 11, the lower parts of the frames H are received and secured by bolts or rivets, and these frames rise above the joint-block and receive the chain-wheels L M and their drums L' M', respectively. The chain-wheels L M are considerably larger in diameter than the drums L' M', in order that the necessary leverage may be obtained in operating the machine, as hereinafter specified. The hoisting-chains 15 16 pass around the respective wheels L M, and the lower ends are attached to the same and the upper ends join together at the main hoisting-chain 17. The wheels L M lap past each other, as seen in Fig. 1, so that they occupy but little space, and the chain-drum L' of the wheel L is near the edge of the wheel M, and the chain-drum M' is near the edge of the chain-wheel L, and from these drums L' M' the chains 20 and 21 pass up to the head-block P. This head-block P is rectangular, with an opening through the middle for the chains 15 and 16 to pass through, and there are rollers 22 and 23 upon the said head-block, to prevent wear against the chains as the parts move in opposite directions.

From the head-block P there are toggle-bars Q, that extend to the respective claw-shaped arms B, the toggle-bars being hinged at their upper ends to the head-block and at their lower ends to the claw-shaped arms, and these joints are made in a peculiar manner, as hereinafter described, so as to allow the parts to move freely as the head-block is drawn up by the chain 30 to open the grapple, and as the head-block is drawn down by the chains 20 21 and drums L' M' to close said grapple. The toggle-bars Q are made of the requisite size and strength, and preferably ribbed longitudinally and thickest in the middle to obtain the necessary strength, and at each end of each bar the bearing-pieces 35 project laterally and taper outwardly, the outline of the taper being an arc of a circle. The upper ends

of these toggle-bars Q rest in correspondingly-shaped recesses in the under surface of the head-block P, and around and beneath the lateral projecting bearing-pieces the hinge-loops 36 pass, the parallel portions of such loops going up through the head-block P and being secured by nuts. The lower ends of the toggle-bars Q rest in correspondingly-shaped recesses near the outer angles of the grapple-bars B, and there are hinge-plates 37 bolted at opposite sides of each of the grapple-arms B and provided with holes that receive the tapering and laterally-projecting bearing-pieces of the toggle-bars Q.

15 The object in constructing the joints of the toggle-bars in the manner before described is to allow a limited lateral or rolling motion to the toggle-bars, as well as the turning motion of the joints themselves. This prevents the 20 toggle-bars becoming bound or confined in the joints at the ends through any unequal or lateral movement that accompanies the grasping action of the excavator, as the same may be closed upon a rock, stone, or other hard substance to raise the same.

25 By my improvement it will be apparent that guides for the head-block are dispensed with, and the parts are made very strong and as light as consistent with the duty to be performed, and in case of accident to either 30 bucket-section it can easily be replaced or repaired, and the joint-block and head-block, and also the toggle-arms, can be repaired or replaced if necessary.

35 When this submarine excavator is used upon hard material—such, for instance, as phosphate rock—the edges of the buckets or the grapple-points are caused to penetrate by the blow struck as the apparatus is allowed to descend rapidly. In this case there is a considerable strain and concussion on the chains passing from the drums to the head-block. I relieve the parts from this concussion by making use of the stop-bars S, that are fastened 40 upon the frame H and project in such a manner that the arms B, or projections on such arms, come directly against the ends or projecting legs of the stop-bars. Thereby the concussion, as the parts of the grapple strike any 45 rigid substance in lowering the open bucket, is taken upon the rigid stop-bars, and the other parts of the apparatus are relieved from strain or injury. These stop-bars should bear against the ends of the pivot-pins on which the wheels 50 revolve, so that there may be no tendency for the frames H to be sprung toward each other.

In consequence of the toggle-arms Q having projecting bearing-pieces, forming T-shaped ends, the entire grapple is rendered much more 6c reliable, because the unequal strains to which the various parts are subjected in grappling irregular pieces of rock and other articles do not cause the ends of the toggle-arms to bind upon their pivots and injure the joints, as is 65 the case where pivot-pins are made use of, and the parts are kept much more reliably in their relative positions than they are when ball-joints are employed.

I claim as my invention—

1. The joint-block A and the grapple formed of spherical sections hinged to such joint-block, in combination with the frame, the two parallel chain-wheels lapping past each other, and the two chain-drums, the toggle-arms, head-block, and the hoisting-chain and the chains connecting the drums to the head block, substantially as set forth.

2. The combination, in a submarine excavating apparatus, of a bucket composed of two 80 or more hinged sections, a joint-block to which the bucket-sections are hinged, toggle-arms having T-shaped projections at the ends, and a head-block for opening and closing the bucket-sections, and connections for the ends of the 85 toggle-arms, chains passing through an opening in the head-block, parallel and adjacent wheels to which such chains are connected, and drums and chains extending from the drums to the head-block, and a frame above 90 the joint-block, supporting the axes of the wheels, substantially as set forth.

3. The combination, in the submarine excavator having arms and a joint-block to which the arms are hinged, of a head-block and toggle-arms extending from the excavator-arms to the head-block, and having laterally-projecting and tapering bearing-pieces 35, forming T-heads at the ends of such toggle-arms, and the hinge-loops, substantially as specified.

4. The combination, with the hinged sections, in a submarine excavating apparatus, of the joint-block to which the sections are hinged and stop-bars against which the sections rest when opened, substantially as and for the purposes specified.

Signed by me this 4th day of March, A. D. 1886.

C. A. MORRIS.
